UNITED STATES PATENT OFFICE.

WESLEY F. HALL, OF MATAWAN, NEW JERSEY, ASSIGNOR TO THE HANSON & VAN WINKLE COMPANY, OF NEWARK, NEW JERSEY, A CORPORATION OF NEW JERSEY.

ELECTROPLATING MACHINE.

Application filed May 17, 1926. Serial No. 109,720.

This invention relates to electroplating machines whereby articles are automatically and mechanically put into and taken out of one or more baths, and more particularly 5 to that class of machines in which the articles are carried by transverse rods or supports that are adapted to engage at their ends with lifting and conveying mechanism along the two sides of the tanks. It is imperative 10 that the lifting mechanisms on the opposite sides of the tank engage both ends of a rod simultaneously as otherwise the rod might be lifted askew or in some cases one end engaged and one end not engaged 15 with disastrous results. Such contingencies are quite likely to occur because of the lost motion, swaying, or other irregularities of the sprocket chains, suspending hooks or other mechanisms used for conveyors or 20 lifters.

It is the object of the present invention to insure such simultaneous engagement of the lifting mechanisms with the transverse carrier rods.

25 The invention comprises certain combinations of devices for holding a rigid transverse alignment between any two lifters adapted to engage the ends of any rod so that there will be no danger of this alignment being disturbed by reason of lost motion, swaying or other irregularities of the 30 parallel conveying mechanisms.

The invention will be better understood by a description in connection with the accompanying drawings representing a particular embodiment thereof.

Figure 1 is a vertical transverse section and elevation.

Figure 2 is a detail partly in section of the 40 lifting mechanism, and

Figure 3 is a longitudinal section on line 3—3 of Figure 2.

An electroplating tank is represented at 1, having the usual anode bars 2 supported 45 therein. At 3 are shown the hangers for supporting the articles to be plated, and these hangers are carried by transverse cathode bar 4 bridging the tank from side to side. On suitable frames 5 on each side 50 of the tank are mounted in proper journals 6, transverse shafts 7, of which there may be two or more. These shafts carry sprocket wheels 8 for sprocket chains 9. The upper lengths of these sprocket chains run in channels 10 (see Figure 2), suitable rollers 11

on the chain supporting the same in the channels. The channels are connected to the cathode end of the source of electric current. The transverse cathode supporting rods 4 are extended over the sides of the tank and rest in depressions in the links of the sprocket chain, so that the chains as they are propelled carry the cathode supports and the articles being plated along through the tank longitudinally. 60 The articles to be plated are deposited into and taken out of the tank by means of a vertical conveyor at each end of each tank. This conveyor comprises two sprocket chains 20, one on either side carried by sprocket wheels 12 mounted on shafts 13, running in bearings 14, carried by the frames 5. The lifting of the cathode supporting rods 4 is accomplished by hooks 15, having forked ends as shown at 16 in Figure 3, adapted 70 to engage the ends of the cathode rods 4 behind end flanges 17 on said rods. The hooks 15 are, therefore, in pairs and are attached at transversely opposite points by pivotal supports 18 to the links of the chains 80 20. The two hooks of each pair are rigidly connected by a transverse beam 19, the object of which is to insure that the two hooks of one pair shall simultaneously engage the two ends of the cathode rod 4. These pivotal supports are pivoted to the links as shown at 21 and a journal extension 22 carries the hooks 15 by means of two ball bearings 23. The construction is, therefore, such that the transverse bar 19 can maintain the 90 rigid frame formed by the bar 19 and the hooks 15 all square with the tank and not allow any irregularities of the conveying mechanism or swinging of the hooks to interfere with its accurate alignment with the 95 rods with which it is intended to engage. Without such rigid transverse connection, the swaying of the chains or the lost motion therein renders it liable for one of the hooks to be displaced sufficiently to pass by the 100 end of the rod 4 during the lifting operation, resulting disastrously unless the machine is instantly stopped.

I claim:—

1. In combination with an electro-plating 105 tank, a horizontal conveyor comprising horizontal conveyor chains located on each side of the tank, a bar resting transversely on said horizontal conveyor chains for supporting an article to be treated in said tank, 110

a vertical conveyor situated above said horizontal conveyor comprising vertical conveyor chains, hooks on said vertical conveyor chains adapted to engage the ends of said 5 transverse bar simultaneously and raise the same, and a transverse beam rigidly attached at its ends to said hooks, whereby the transverse alinement of the hooks is assured.

2. In combination with an electro-plating 10 tank, a horizontal conveyor, a bar resting transversely on said horizontal conveyor for supporting an article to be treated in said

tank, vertical conveying sprocket chains situated above said horizontal conveyor, and a rigid lifting frame pivoted at each end to 15 certain of the links of said sprocket chains comprising hooks adapted to engage the ends of said transverse bar simultaneously and raise the same, and a transverse beam rigidly attached at its ends to said hooks, 20 whereby the transverse alinement of the hooks is assured.
